CIRCULAR RADIO TUNING FREQUENCY CONTROL WITH TRANSVERSE INDICATOR FACES

Maurice D. Katz, 35 Broadway, Lawrence, N.Y. 11559

Filed Mar. 12, 1971, Ser. No. 123,939

Term of patent 14 years

Int. Cl. D14—03, 99

U.S. Cl. D26—1

FIG.1

FIG.2

FIG. 1 is a front perspective view of the circular radio tuning frequency control with transverse indicator faces, embodying the features of my new design.

FIG. 2 is a front perspective of the face plate disclosed in FIG. 2 mounted in a radio.

The broken lines representing the radio are shown for illustrative purposes only.

I claim:

The ornamental design for a circular radio tuning frequency control with transverse indicator faces, substantially as shown and described.
